WATER VAPOR SUPPLY DEVICE FOR FUEL CHARGES OF
INTERNAL COMBUSTION ENGINES
Filed July 21, 1926

Fig. 2.

UNITED STATES PATENT OFFICE

PERCY L. JONES, OF MEDFORD, MASSACHUSETTS

WATER-VAPOR-SUPPLY DEVICE FOR FUEL CHARGES OF INTERNAL-COMBUSTION ENGINES

Application filed July 21, 1926. Serial No. 123,927.

This invention relates to a novel device for utilizing water vapor from a radiator to supply moisture to the fuel charge of an internal combustion engine. The invention will be best understood by reference to the following description when taken in connection with the accompanying drawings of one specific embodiment thereof, while its scope will be more particularly pointed out in the 10 appended claims.

In the drawings:

Fig. 1 is an elevation, partly in vertical section of a portion of a motor vehicle having an internal combustion engine equipped 15 with a water vapor supply device exemplifying the invention;

Fig. 2 is an elevation partly in vertical section of the upper portion of the device showing part of the top of the radiator neck with 20 the vapor supply device mounted thereon;

Fig. 3 is a sectional view on line 3—3 of Fig. 2; and

Fig. 4 is a similar sectional view showing a slight modification of the construction illustrated in Fig. 3.

Referring to the drawings and to the embodiment of the invention which is selected for exemplification, and having reference at first to Fig. 1, there is shown a portion of a 25 motor vehicle having an internal combustion engine 5 to which the fuel charge is supplied by a carburetor 6, whence it is conducted by an intake manifold 7 to the combustion chambers. The engine cylinders have a 30 water jacket 8 which communicates with a radiator 9 in the usual manner. The radiator presents a water reservoir for the cooling water which is circulated through the water jacket. The radiator has a neck 10 (see Figs. 2 and 3) through which water is introduced 35 into the cooling system. An overflow pipe 11 (see Fig. 1) leading from the neck discharges at a convenient point therebelow, outside of the radiator. The engine and its 40 cooling system as thus far described are of usual and well-known construction.

Attached to the radiator neck, as by a screw thread 12 is a cap 13 comprising upper and lower sections 14 and 15 hingedly connected as by a pintle 16. An appropriate

fastener, herein a wire bail 17 of known construction, normally secures the sections together. The upper section may be lifted and turned about the axis of the pintle to permit the introduction of water into the radiator.

Surmounting the cap, as thus constituted, is a frame 18 having a head 19, a neck 20 above the upper section of the cap, and a reduced shank 21 which extends through the latter. The shank is suitably secured to the upper section of the cap, as by a threading, to receive a nut 22 on the under or inner side of the upper section. Upper and lower gaskets 23 and 24 above and below the upper section of the cap and made of suitable compressible material, prevent leakage through the joint where the shank passes through.

The head 19 presents a chamber 25 and the neck 20 and shank 21 present a passage 26 leading from the chamber and affording communication between the latter and the radiator neck to permit vapor from the radiator to ascend into the chamber. This passage is rather restricted, that is to say, the cross-sectional dimensions are considerably less than those of the radiator neck, as a result of which water splashing about in the radiator does not reach the chamber. The height of the chamber is such that water which is splashed by motion of the car gravitates from the neck back to the body of the radiator without danger of its reaching the vapor outlet pipe presently to be described.

Herein the vapor chamber is transparent walled to permit the water in the chamber to 85 be viewed if the radiator should boil over for any reason, such as slipping or breaking of the fan belt, and normally to serve as a visual indication that the cooling system is functioning properly. Herein the chamber has 90 opposite openings 27 covered by transparent walls, herein glass plates 28, conveniently secured in place by having their margins bevelled, as at 29, to receive correspondingly bevelled retaining plates 30 conveniently secured 95 to the frame, as by screws 31. Gaskets 32 made of suitable compressible material received in depressions 33 in the frame present cushioning abutments for the plates and prevent leakage at the joints. The plates may 100

readily be dismounted by removal of the screws 31 and retaining plates 30, thereby affording access to the chamber, should occasion require, for the removal of foreign matter, and to enable the inner faces of the glass to be kept clean.

The lower portion of the chamber is provided with downwardly converging sides 34 to conduct back to the passage 26 and thence to the radiator any water of condensation which might form in the chamber, and any water which might enter the chamber if the radiator should boil over. The upper portion of the chamber is provided with upwardly converging sides 35, and at a point adjacent the apex formed by the intersection of these walls an inlet orifice 36 of a tube 37 provides an outlet for the vapor at an elevation sufficiently great to insure that no water splashed about in the radiator shall reach the inlet orifice.

The vapor outlet pipe is conveniently placed along two of the inclined surfaces 34 and 35, where it does not interfere with the full vision of the vapor chamber. This location is preferred also because the device is more attractive with a clear opening from side to side of the vapor chamber.

The vapor outlet tube in the form shown in Figs. 1, 2 and 3, leads in a downward direction through the neck 20 to the exterior of the latter, and herein the neck is provided with a laterally extending boss 38 in which the tube is appropriately secured. To the outer end of the tube there is attached a flexible tube 39 (see Fig. 1) adapted to be flexed when the upper section of the hinged cap is swung to open the cap for the admission of water to the radiator.

The other end of the flexible tube is attached to a tube 40 leading to the intake manifold 7, preferably intermediate the carburetor and the combustion chambers of the cylinders. Herein a pipe is provided with a valve 41 conveniently located near the operator's position, as on an instrument board 42, to enable the amount of vapor supplied to the fuel charge to be controlled at will.

The modification illustrated in Fig. 4 is similar in most respects to that hereinbefore described, except that the vapor outlet pipe, instead of extending laterally through the neck of the frame, leads downwardly through the vapor inlet passage and through the radiator neck to a convenient point within the radiator, whence it may be carried through the radiator wall and thence to the carburetor. In this form, however, the cap, instead of being hinged, is simply secured on to the radiator neck, and must be unscrewed to enable the radiator to be filled with water. When the cap is removed, of course, the vapor outlet pipe must remain in place and must necessarily be straight, in order that the frame and cap may be lifted clear of it.

In operation, the device supplies vapor to the fuel charge, thereby tending to promote economy of operation of the engine and to minimize accumulation of carbon deposits in the combustion chamber without danger of unvaporized water reaching the engine intake and interfering with the operation of the engine.

Having thus described one embodiment of the invention, but without limiting myself thereto, what I claim and desire by Letters Patent to secure is:

1. In a vapor supply device for internal combustion engines, the combination of a cap for attachment to a radiator to furnish the vapor, said cap comprising upper and lower hingedly connected sections, said upper section presenting an opening, a frame having a head and a neck above said upper section and a reduced shank extending through said upper section and secured to the latter, said head presenting a chamber and said neck and shank presenting a passage leading from said chamber through said neck and shank and adapted to permit vapor from the radiator to ascend into said chamber, said chamber having oppositely disposed, transparent walls through which water may be viewed, said chamber also having upwardly converging sides in its upper portion, and downwardly converging sides in its lower portion, a tube having an inlet orifice for vapor adjacent the upper portion of said chamber, said tube extending in a downward direction along one side of said chamber and through said neck to the exterior, and a flexible tube attached to the outer end of said conduit and adapted to be flexed when the upper section of said hinged cap is swung to open said cap for the admission of water to the radiator.

2. In a vapor supply device for internal combustion engines, the combination of means presenting a vapor chamber having a lateral opening, a transparent wall extending across said opening, means providing for the lateral removal of said wall to afford access to said chamber, a vapor inlet conduit leading into said chamber, and a vapor outlet conduit leading out of said chamber.

3. In a vapor supply device for internal combustion engines, the combination of means presenting a vapor chamber, an inlet conduit thereto and an outlet conduit therefrom, said outlet conduit having a flexible portion, and a hinged mounting for said means, said mounting having provision for attachment to a radiator to supply vapor through said inlet conduit to said chamber.

In testimony whereof, I have signed my name to this specification.

PERCY L. JONES.
